UNITED STATES PATENT OFFICE.

THOMAS J. BURKE, OF NEW ORLEANS, LOUISIANA.

TOY BOWLING-ALLEY.

1,209,113.

Specification of Letters Patent. Patented Dec. 19, 1916.

Application filed March 25, 1916. Serial No. 86,723.

To all whom it may concern:

Be it known that I, THOMAS J. BURKE, a citizen of the United States, residing at New Orleans, in the parish of Orleans and State 5 of Louisiana, have invented certain new and useful Improvements in Toy Bowling-Alleys, of which the following is a specification.

This invention relates to game apparatus 10 and more particularly to a toy bowling alley.

It is one aim of the present invention to provide in apparatus of this class a novel pin setting device which may be readily actuated to automatically, quickly and accurately reset all of the pins simultaneously and subsequently actuated to release all of the pins or, in other words, relieve the same of tension and leave them standing in proper position upon their bases and entirely free from support so that a game projectile constituting a part of the apparatus may strike and knock down a greater or less number of the pins, depending upon the skill of the person 20 actuating the device provided for the purpose of throwing the projectile.

Another aim of the invention is to provide in connection with the pin setting device, an element arranged for actuation to actuate the pin setting device to set the pins, which element will constitute a target at which the projectile may be aimed so that a player by exercising skill may cause the projectile to strike the target and in this 30 manner automatically reset the pins or other objective game pieces without the necessity of arising from his seat or manually actuating the said element.

Another aim of the invention is to so construct the apparatus that after the projectile has been thrown at the pins it will be stopped and automatically returned to that end of the apparatus at which the player then trying his skill is located.

Another aim of the invention is to so construct the pin setting device of the apparatus that the strain upon the flexible elements which are connected to the pins and which are pulled in the act of resetting the pins, will be evenly distributed throughout the entire number of such elements so as to insure of proper and simultaneous setting of all of the pins and to obviate likelihood of

the flexible elements being broken through the sudden actuation of the pin setting device.

Another aim of the invention is to so construct the apparatus that the pin setting device thereof will be completely housed and will, therefore, not be liable to become accidentally disarranged or broken although access may be readily had thereto in the event that it becomes necessary to repair any of the parts of the said device.

In the accompanying drawings: Figure 1 65 is a vertical longitudinal sectional view through the apparatus embodying the present invention, the pin setting device being illustrated in condition immediately after having been actuated to set the pins. Fig. 2 70 is a bottom plan view of the apparatus. Fig. 3 is a fragmentary perspective view of the pin setting device. Fig. 4 is a vertical transverse sectional view through the apparatus. Fig. 5 is a vertical longitudinal sectional 75 view through the device for throwing the game projectile.

The game apparatus embodying the present invention includes an inclined base which is indicated by the numeral 1 and which is 80 supported in elevated position preferably by means of side boards 2, a back board 3 and a front board 4 although, if desired, the base may be supported in any other suitable manner.

While the device for throwing the game projectile of the apparatus may be of any desired type it is here shown as in the nature of a spring gun comprising a barrel 5 which is provided between its ends with a block 6 90 mounted within an opening 7 formed in an upright supporting member 8. Pins 9 and 10 are secured through the upper and lower edges respectively of the said member 8 and fit in sockets 11 formed in the upper and 95 under sides of the block 6 whereby to permit of swiveling movement of the barrel 5. Within the barrel there is mounted a plunger 12 the stem 13 of which fits slidably through an opening in the closed rear end of the barrel 5 and is provided with a finger knob 14 by means of which the plunger may be retracted. The plunger is normally held in a forward position by means of a spring 16 which is fitted to the stem 13 and bears at 100 one end against the plunger head 12 and at 105

its other end against the said closed rear end of the barrel. The supporting member 8 is, of course, mounted at that end of the base 1 at which the player stands in using 5 the apparatus and as stated the barrel 5 may have swiveling movement so that the player may exercise his skill in aiming the device.

The projectile is indicated by the numeral 16 and may be in the form of a marble, rubber ball or, in fact, any similar article suitable for the purpose and spherical in shape. The barrel 5 is preferably provided in its upper side with an opening 17 through which the projectile 16 may be inserted when 10 the plunger 12 is retracted against the tension of the spring, it being understood that upon release of the finger knob 14 the spring will drive the plunger forwardly thereby throwing the projectile from the barrel in 15 the direction of the other end of the base 1 or, in other words, that end at which the pins or other objective game pieces are arranged. The inclination of the base 1 is in 20 a downward direction from its last mentioned end and consequently after the projectile has been thrown and falls upon the base, it will roll by gravity to the lower end of the base where it may be conveniently recovered by the player.

30 In order that the projectile may be arrested in its course after having struck the pins or other objective game pieces, and therefore be prevented from being thrown beyond the apparatus and cause damage or 35 become lost, means is provided which will now be described. Supported in upright position, either removably or in a permanently fixed manner at each side of the base 1 at its upper end, is a post or upright 18 provided 40 near its upper end with a groove or notch 19 and near its lower end with a groove or notch 20. A netting 21 is provided at its upper and lower edges with hems 22 and 23 respectively through which are passed draw 45 strings 24 and this netting is preferably straight throughout the extent of its lower edge but has its upper edge inclined downwardly from points at opposite sides of its middle toward each end. In arranging the 50 netting in position the intermediate portion of the netting is stretched between the posts 18 with the hems 22 and 23 seating in the notches 19 and 20 respectively and the draw strings 24 are then more or less tightly 55 drawn in the direction of the lower end of the base 1 and are passed through eyelets 25 at the lower corners of the base and tied in any suitable manner. When so arranged the netting will present a stretch the 60 height of the posts 18 and extending between the posts, and side stretches which extend along the opposite sides of the base 1, and the upper edges of which gradually incline downwardly toward the lower end of the 65 base.

In the present invention the objective game pieces are in the nature of miniature bowling pins and are indicated by the numeral 26, and each pin is formed with an axially extending bore 27 through which 70 is led a flexible cord 28, the cord being either provided with a knot 29 seating at the upper end of the bore 27, or secured in any other suitable manner to the pin. There are preferably ten of the pins provided as upon the 75 ordinary bowling alley and when the pins are in position they occupy the same relative position as do the pins upon the ordinary bowling alley. Therefore, the base 1 of the apparatus is formed with a number of openings 30 arranged in the manner stated and through which openings the cords or other flexible elements 28 are led as clearly shown in Figs. 1 and 4 of the drawings. In order that the pins may be reset after each play or 80 series of plays, means is provided for exerting simultaneously a pull upon all of the cords 28 and while various devices may be employed for this purpose the one here shown includes a resilient member preferably 85 in the nature of a strip 31 of some resilient wood which is secured at one end to a cross piece 32 arranged beneath the base 1 at the lower end thereof, the tendency of the strip 31 being to spring downwardly at its 90 free end. It will be understood, of course, that the strip 31 extends longitudinally beneath the base 1 and the strip is preferably provided near its end which extends beneath the upper end of the base 1, with a number 100 of cross pieces 33, 34 and 35, which may be of wood or any other suitable material and which extend respectively transversely beneath the several rows of pins. That is to say, the cross piece 33 extends beneath the 105 rear row of four pins; the cross piece 34 extends transversely beneath the next row of three pins; and, the cross piece 35 extends transversely beneath the next row of two pins. The several cross pieces are provided 110 with openings 36 and the strip is provided with a single opening 37 through which openings the cords or flexible elements are led. These cords may be arranged in any suitable manner although an arrangement 115 such as illustrated in Fig. 2 of the drawings is to be preferred. In this arrangement the cords from the two middle pins of the rear row are led through the corresponding openings in the cross piece 33 and are united 120 and have connected to them one end of a coil spring 38, the other end of which spring is secured as at 39 to the strip 31. The two end pins in the next adjacent row have their flexible elements 28 led through corresponding openings in the cross piece 34 and connected to each other and have connected therewith a spring 40 which is also connected to the strip 31. The flexible elements 28 from the two end pins of the rear row of 125 130

pins are led through corresponding openings in the cross piece 33 and are connected to each other and in a like manner the flexible elements of the two pins of the second 5 row are led through correspondingly located openings in the cross piece 35 and are connected to each other and to these two sets of connected flexible elements are connected the ends of a coil spring 41. The flexible 10 elements from the head pin or, in other words, the foremost pin, and from the middle pin of the row of three pins are led respectively through the opening 37 and the other one of the openings in the cross piece 15 34 and are connected to each other and have connected to them a coil spring 42, which is also connected preferably to the cross piece 35.

It will now be apparent that while all of 20 the flexible elements 28 are connected to the strip 31 or more specifically to its cross pieces 33, 34 and 35, this connection is not a direct one but is through the medium of resilient elements such as the several springs referred 25 to. As a consequence, when the strip 31 is permitted to spring downwardly at its free end a pull will be exerted upon each and every one of the flexible elements causing the respective pins 26 to assume an upright 30 position upon the base member 1 and yet in constructing the apparatus it is not necessary to exercise great care in proportioning the length of the several strings or connections in order to insure of substantially the same 35 pull being exerted upon all of the strings. This obviously would be necessary, however, if the flexible elements were connected directly to the strip 31 or its cross pieces and without the interposition of yieldable means 40 for establishing the connection. It will also be understood that when the member 31 is placed under tension by springing its free end upwardly, the flexible connections will be relieved of strain and the pins are supported solely by the disposal of their bases 45 upon the base 1 and consequently when struck by the projectile of the apparatus they are free to fall. At this point it will be apparent that where means is provided for 50 holding the strip 31 under tension and this means is operable to suddenly release the strip, the strip at its free end will spring quickly in a downward direction and exert a quick pull upon the several flexible elements 55 which are connected to the pins. The shock of this sudden pull is, however, absorbed by the several springs which establish connection between the flexible elements and the strip 31 or its cross pieces and, 60 therefore, it is not likely that the flexible elements will be broken due to the sudden pull exerted. In order that the strip 31 may be placed under tension and the flexible elements thereby relieved from the pull 65 which this strip normally tends to exert

upon them, a cord or other flexible element 43 is connected at one end as at 44 to the free end of the strip 31 and is led through an eye 45 upon the under side of the base 1 and thence in the direction of the lower end 70 of the base or, in other words, the front board 4 of the apparatus, and through an opening 46 in the said front board and is provided at its end with a loop or any other suitable device 47 whereby to permit of its 75 being grasped and a pull exerted thereon. It will now be understood that by pulling upon the cord 43 the free end of the strip 31 will be flexed in an upward direction. In order that the strip may be held under tension 80 there is provided a detent device which may be formed of wood or metal and is preferably in the nature of a resilient arm 48 secured at its lower end to the inner side of the back-board 3 and provided at its upper end with 85 a head 49 which for a reason to be presently explained projects upwardly through a slot 50 formed in the base 1 a suitable distance in the rear of the group of pins 26. At a suitable point below the base 1 the forwardly 90 presented face of the head 49 is formed with a notch 51 into which may seat the free extremity of the strip 31 when the strip is flexed upwardly, the arm 48 having a normal tendency to spring forwardly into the path 95 of movement of the said extremity of the strip 31 when the strip is flexed. The strip having been flexed in the manner stated so as to bring its free extremity into engagement in the notch 51, the flexible connections 28 100 will be relieved of the pulling strain normally exerted by the strip, and the projectile throwing device of the apparatus may then be employed for the purpose of throwing the projectile in the direction of the group of 105 pins. As before stated, the detent includes a resilient head 49 which projects upwardly through the slot 50 formed in the base 1 a suitable distance in rear of the group of pins 26 and this head constitutes a target at which 110 the projectile may be thrown in the same manner in which it is thrown at the pins or other objective game pieces, for the purpose of automatically resetting the pins or other objective game pieces. For example, after 115 a player has made his play or plays he will operate the projectile throwing device with the intention of causing the projectile to strike the head 49 and when he is successful in making such a play the head will be 120 thrown rearwardly thereby rendering the detent inactive to retain the strip 31 in flexed condition and the strip will then pull upon the flexible elements which are connected to the objective game pieces, causing the same 125 to assume automatically an upright position upon the base board of the apparatus.

It will be understood that while the objective game pieces are herein shown and described as in the nature of miniature ten 130

pins, they may represent soldiers, animals, or, in fact, any other animate or inanimate thing or object.

Having thus described the invention, what is claimed as new is:

1. In game apparatus, a base member, an objective game piece arranged for disposal in upright position upon the base member, a flexible element connected to the game piece and extending through the base member, a resilient element secured at one end beneath the base member and having connected to its free portion the said flexible element, and means operable to render the said resilient element inactive.
2. In game apparatus, a base member, an objective game piece arranged for disposal in upright position upon the base member, a flexible element connected to the game piece and extending through the base member, a resilient element secured at one end beneath the base member and having connected to its free portion the said flexible element, means for placing the resilient element under tension whereby to relieve the flexible element of pulling strain, and means for maintaining the tension upon the said resilient element.
3. In game apparatus, a base member, an objective game piece arranged for disposal in upright position upon the base member, a strip of resilient material secured at one end beneath the base member, a flexible element connected to the said objective game piece and to the said resilient strip, a pulling element connected to the free portion of the strip and arranged when a pull is exerted thereon to flex the strip and place the same under tension in a manner to relieve the flexible element of pulling strain, and a detent arranged for coaction with the said strip to hold the same flexed and operable to release the said strip.
4. In game apparatus, a base member, an objective game piece arranged for disposal in upright position upon the base member, a resilient strip secured beneath the base member and having a free end portion, a flexible element connected to the game piece, yielding connection between the flexible element and the said free portion of the resilient strip, the strip tending to normally assume a position exerting a pull upon the said connection and the said element, means for flexing the said portion of the strip to relieve the element of pulling strain, and a detent operable to maintain the said portion of the strip in flexed condition.
5. In game apparatus, a base member, an objective game piece arranged for disposal in upright position upon the base member, a resilient element mounted at one end beneath the base member and having a free portion, a flexible element connected to the game piece and to the free portion of the said member, means for flexing the said portion of the member to relieve the said element of pulling strain normally exerted by the said member, and a resilient detent mounted beneath the base member and having a portion projecting upwardly through the base member and having a shoulder arranged for engagement by the end of the said portion of the resilient member for holding the same flexed.
6. In game apparatus, a base member, an objective game piece arranged for disposal in upright position upon the base member, means tending to cause the said game piece to assume such position, means for rendering the last mentioned means inactive and including a target element projecting above the base member, and projectile throwing means operable to throw a projectile in the direction of the said target element and said game piece.
7. In game apparatus, a base member, an objective game piece arranged for disposal in upright position upon the base member, a flexible element connected to the game piece, means normally tending to exert a pull upon the said element whereby to cause the game piece to assume an upright position on the said base member, and means operable to render the pulling means inactive and including a target element projecting above the base member in rear of the said game piece.
8. In game apparatus, a base member, an objective game piece arranged for disposal in upright position upon the base member, a resilient element arranged beneath the base member, a flexible element connected to the game piece and to the resilient element, means for placing the resilient element under tension whereby to relieve the flexible element of pulling strain, and a detent for maintaining the resilient element under tension including a target portion projecting above the said base member.
9. In game apparatus, a support, a game piece arranged for disposal in upright position upon the support, means tending to cause the said game piece to assume such position, means for rendering the last mentioned means inactive, means for retaining the same inactive, a target element operatively associated with the last mentioned means, and a projectile throwing means operable to throw a projectile in the direction of the said target member.

In testimony whereof I affix my signature.

THOMAS J. BURKE. [L.S.]
